UNITED STATES PATENT OFFICE

114,195

DESIGN FOR A HAIR BRUSH

Peter Müller-Munk, Pittsburgh, Pa., assignor to Pro-phy-lac-tic Brush Company, Northampton,
Mass., a corporation of Delaware

Application February 2, 1939, Serial No. 82,740

Term of patent 7 years

To all whom it may concern:

Be it known that I, Peter Müller-Munk, a citizen of the United States of America and a resident of Pittsburgh, in the county of Allegheny, State of Pennsylvania, have invented a new, original, and ornamental Design for Hair Brushes, of which the following is a specification, reference being had to the accompanying drawing, forming part thereof.

In the drawing:

Fig. 1 is a top or back view,
Fig. 2 is a side view,
Fig. 3 a face view, and
Fig. 4 an end view of a hair brush showing my new design.

I claim:

The ornamental design for a hair brush, substantially as shown.
